Sven Wilhelm Landeborn, Stockholm, Sweden

Application September 25, 1946, Serial No. 133,569
In Sweden April 1, 1946

Term of patent 14 years

(Cl. D74—1)

To all whom it may concern:

Be it known that I, Sven Wilhelm Landeborn, a subject of the King of Sweden, residing in the city of Stockholm, Sweden, have invented a new, original, and ornamental Design for a Pencil Sharpener, of which the following is a specification, reference being had to the accompanying drawings, forming part thereof.

Fig. 1 is a side perspective view of a pencil sharpener, showing my new design;

Fig. 2 is a top plan view thereof;

Fig. 3 is an end elevational view; and

Fig. 4 is an end elevational view of the end opposite that shown in Fig. 3.

I claim:

The ornamental design for a pencil sharpener, as shown.

SVEN WILHELM LANDEBORN.
